UNITED STATES PATENT OFFICE

164,467

ADJUSTABLE SLIDE WEDGE BLOCKING TOOL

Richard S. Arnold, Denver, Colo.

Application March 4, 1950, Serial No. 8,324

Term of patent 7 years

(Cl. D54—2)

To all whom it may concern:

Be it known that I, Richard S. Arnold, a citizen of the United States, and resident of Denver, in the county of Denver and State of Colorado, have invented a new, original, and ornamental Design for an Adjustable Slide Wedge Blocking Tool, of which the following is a specification, reference being had to the accompanying drawing, forming a part thereof.

Fig. 1 is a top plan view of an adjustable slide wedge blocking tool, showing my new design.

Fig. 2 is a side elevational view of the same, the opposite side being substantially identical although reversed.

Fig. 3 is an end-on elevational view of the same as viewed from the left end of Fig. 2.

Fig. 4 is an end-on elevational view of the same as viewed from the right end of Fig. 2.

Figs. 5 and 6 are sectional views taken through the tool along the lines 5—5 and 6—6 respectively of Fig. 2 and in the directions indicated by the respective arrows.

The characteristic features of my design reside in the outwardly bossed finger grip elements in their relation to and association with the adjoining portions all as shown.

I claim:

The ornamental design for an adjustable slide wedge blocking tool, substantially as shown and described.

RICHARD S. ARNOLD.
